UNITED STATES PATENT OFFICE.

TOLBERT LANSTON, OF WASHINGTON, DISTRICT OF COLUMBIA, ASSIGNOR
TO THE LANSTON MONOTYPE MACHINE COMPANY, OF SAME PLACE.

RECORD-STRIP PERFORATOR FOR TYPE-FORMING MACHINES.

SPECIFICATION forming part of Letters Patent No. 663,971, dated December 18, 1900.

Application filed October 7, 1899. Serial No. 732,926. (No model.)

To all whom it may concern:

Be it known that I, TOLBERT LANSTON, a citizen of the United States, residing at Washington, in the District of Columbia, have invented certain new and useful Improvements in Machines for Preparing the Perforated Record-Strips of Type-Forming Machines; and I do hereby declare the following to be a full, clear, and exact description of the same, reference being had to the accompanying drawings, forming a part of this specification, and to the letters of reference marked thereon.

This invention relates generally to improvements in controllable perforating mechanism, and specifically to the class of manually-controlled or keyboard punching-machines—such, for example, as those employed in connection with the "Lanston monotype" and similar systems for the production or preparation of perforated record-strips or controllers—the latter being utilized to govern or control other mechanisms, such as type-making machinery, in the production of printing characters.

As an exemplification of the general class to which the present invention relates reference may be had to my prior patent, No. 590,763, dated September 28, 1897, and for a more specific type reference may be had to my Patent No. 654,115, dated July 17, 1900.

The object of the present improvement is to provide for the simultaneous production of any desired number of perforated record-strips or controllers by a single operator and without imposing upon the operator greater labor than is necessary for the production of a single strip or controller.

Referring to the accompanying drawings, Figure 1 is a diagrammatic representation of a structure adapted for the simultaneous production of three record-strips or controllers. Fig. 2 is a vertical section through a portion of one of the punching mechanisms and having coupled therewith three other punching mechanisms, portions of the mechanism of which are shown in section and elevation. Fig. 3 is a side elevation, partly in section, showing one of the paper or strip feeding mechanisms. Fig. 4 is a perspective view of one form of gate or valve, such as is employed

for cutting out any desired one of the perforating and paper or strip feeding mechanisms.

Like letters of reference in the several figures indicate the same parts.

In carrying the present invention into practice and as shown in the before-mentioned patent, No. 654,115, the strip or controller is adapted to be fed from a supply-roll A around a die or mandrel B and to be wound upon a winding-shaft C. In its passage around the mandrel it is subjected to the action of a series of punches D, preferably working vertically through suitable apertures in the mandrel and adapted to produce perforations representing all the characters and spaces employed in the completed composition for the production of which the record-strip forms the controller. The punches D are moved vertically by means of levers E, which latter in turn receive their motion from a series of punch-motors preferably consisting of pneumatic cylinders and pistons F and f, respectively, to which compressed motive fluid, such as air, may be admitted from any suitable source upon the manipulation of appropriate finger-pieces G, grouped together and constituting a keyboard. In the preferred construction the finger-pieces G constitute, as it were, valves for admitting pressure into pipes or conduits H, and the latter in turn are connected with the cylinders F in proper order to project the punches in combinations corresponding to the finger-pieces on the keyboard. The finger-pieces on the keyboard are preferably arranged in what may be termed "columns" extending vertically or away from the operator and in "rows" extending at right angles thereto or horizontally, and each finger-piece is adapted to admit pressure in the proper pipe or conduit H for raising a punch corresponding to the column and a punch corresponding to the row in which that finger-piece is located, as will be readily understood from an inspection of Fig. 1 and from which it will be apparent that but a relatively small number of punches need be employed to secure all of the combinations necessary for representing a very large number of characters on the keyboard.

Obviously the number of sets of punches

and strip-feeding mechanisms which may be connected with and operated from the pipes or conduits H is limited only by the length of said conduits and the pressure at which 5 the motive fluid is supplied, and in the accompanying drawings, Fig. 1, is shown, diagrammatically, three sets of punches, while in Fig. 2 four sets of such punching mechanisms are shown, each being a duplicate of the other and corresponding punches of each being operated 10 from the said supply pipe or conduit H. In order to provide for cutting out any one of such mechanisms, there is preferably provided a single valve or slide for each mechanism 15 which will by a single movement cut off communication between all of the supply pipes or conduits H and the entire series of punches for that mechanism. Such a slide or valve is illustrated in perspective at K, Figs. 2 and 4, 20 and it will be noted from Fig. 4 that it has a series of apertures therein corresponding in number to the number of punches or punch-motor cylinders employed in each of the mechanisms, as shown in Fig. 1, and by a 25 movement in or out it is adapted to move such perforations into or out of registry with the pipes or conduits h, connecting the punch-motor cylinders with the supply-pipes H. Obviously any preferred mechanism for moving 30 the slide or valve K may be employed, and I have shown as a convenient device simple pivoted levers L, the upper ends of which constitute handles which may be grasped by the operator and moved in one direction or the other.

The paper-feeding mechanism for each set of punches which operates on the paper strip through the medium of pin-wheels M and gearing N, connected with the winding-shaft, preferably consists of oscillatory pawling mechanism O, Fig. 3, adapted to be operated during the retraction of the punches through a rod o and a strip-feed motor-piston and cylinder P. Pressure is admitted to the cylinder P on opposite sides of the piston from a pipe p and is controlled by a valve Q, connected with a cross-piece R, extending above the levers E and adapted to be elevated each time any one of said levers are elevated, so as to move said 45 piston up or down, as the case may be, to advance the strip for the next perforation or set of perforations. The pipe p for supplying pressure to the paper or strip feed motor P is connected with its main H' through the slide 50 or valve K, which is preferably provided with a rear aperture p', adapted to form a portion of the conduit between the pipe h' and motor-cylinder or to move out of registry and so prevent the passage of motive fluid there-through. Thus by moving the valve K communication between the pressure-supply and the punching and paper-feeding mechanism may be entirely cut off or simultaneously restored. Thus with a large number of punching 55 mechanisms controlled by a single keyboard any desired number of said punching mechanisms may be thrown into or out of ac-

tion and without in any wise affecting the others or imposing upon the operator any greater or less labor. With this arrangement 70 it will be seen that an operator having the keyboard and one of the strip punching and feeding mechanisms directly under his eye may by manipulating the finger-pieces and observing the punching mechanism produce 75 a single record or strip, and with duplicate punching and strip-feeding mechanism controlled by the same keyboard he may produce other record-strips which will be exact duplicates in all particulars both as to justification and character, and these record-strips may be used for the simultaneous control of independent machines. For newspaper-work, 80 where a number of different presses are employed for running off the same matter, obviously this is a very material advantage, and it will also be found to be highly advantageous where matter is to be simultaneously produced or printed at widely-separated 85 points, inasmuch as the compositor may produce the record-strips or controllers and distribute them as desired for the production of the composition. Thus one compositor may produce matter for simultaneously running a large number of different character-producing 90 machines.

Having thus described my invention, what I claim as new, and desire to secure by Letters Patent of the United States, is—

1. In an apparatus for simultaneously producing duplicate record-strips or controllers for type-forming machines, the combination with a series of sets of punches and record-strip-feeding mechanism for presenting the strip to said punches, of a keyboard, independent punch-motors for the punches of each series, mains connecting said keyboard and punch-motors, and controlling mechanism interposed in the connections between the mains and motors for simultaneously throwing the motors of each set of punches into or out of action; substantially as described. 100

2. In an apparatus for simultaneously producing duplicate record-strips or controllers, the combination with independent strip-feeding mechanisms, independent sets of punches, independent motors for the punches of each set and common mains for like punch-motors of all the sets, of a keyboard and finger-pieces controlling the mains and arranged in columns and rows, whereby upon the operation of any finger-piece, motors corresponding to the column, and other motors corresponding to the row in which said finger-piece is located, will be operated to advance corresponding 115 punches in all the sets; substantially as described. 120

3. In a pneumatically-operated mechanism for simultaneously producing duplicate record-strips or controllers for type-forming machines, the combination of the following instrumentalities, to wit, a keyboard embodying finger-pieces, arranged in vertical columns and horizontal rows, a system of mains, 130

- the pressure in which is controlled by the finger-pieces, independent sets of punches and record-strip-feeding mechanisms, motors for each of said punches and strip-feeding mechanisms and independent connections between said motors and mains, corresponding motors in each of the sets being connected with the same main; substantially as described.
- 5 4. In a pneumatically-operated mechanism for simultaneously producing duplicate record-strips or controllers for type-forming machinery, the combination of the following instrumentalities, to wit, a series of sets of record-strip-producing mechanisms embodying punches and record-strip-feeding mechanisms, independent motors for each of the 30 punches of each of the series embodying pneumatic cylinders and pistons, a system of mains with which said cylinders are in communication, corresponding cylinders of the several sets being connected with the same 35 main and a keyboard embodying finger-pieces arranged in vertical columns and horizontal rows, each of said finger-pieces being adapted to open communication with one of the mains corresponding to the column and one of the 40 mains corresponding to the row in which said finger-piece is located, whereby upon the operation of any finger-piece, pressure will be admitted for the operation of punches in each of the sets corresponding to the column and 45 row in which the finger-piece is located; substantially as described.
- 10 5. In a pneumatically-operated mechanism for simultaneously producing duplicate record-strips or controllers for type-forming machinery, the combination of the following instrumentalities, to wit, a system of main conduits, a keyboard embodying finger-pieces controlling the pressure in said mains, a series of independent sets of punches and record-strip-feeding mechanisms, independent motors for each of the punches and record-strip-feeding mechanisms, independent connections between corresponding motors of each set and the same main, and independent controlling-valves located intermediate each set of punch-motors and mains, whereby all of 20 the motors of each set may be simultaneously thrown into or out of operative connection with the main; substantially as described.
- 15 5. In a pneumatically-operated mechanism for simultaneously producing duplicate record-strips or controllers for type-forming machinery, the combination of the following instrumentalities, to wit, a system of main conduits, a keyboard embodying finger-pieces controlling the pressure in said mains, a series of independent sets of punches and record-strip-feeding mechanisms, independent motors for each of the punches and record-strip-feeding mechanisms, independent connections between corresponding motors of each set and the same main, and independent controlling-valves located intermediate each set of punch-motors and mains, whereby all of 25 the motors of each set may be simultaneously thrown into or out of operative connection with the main; substantially as described.

for simultaneously producing duplicate record-strips or controllers for type-forming machinery, the combination of the following instrumentalities, to wit, a series of sets of record-strip-producing mechanisms embodying punches and record-strip-feeding mechanisms, independent motors for each of the 30 punches of each of the series embodying pneumatic cylinders and pistons, a system of mains with which said cylinders are in communication, corresponding cylinders of the several sets being connected with the same 35 main and a keyboard embodying finger-pieces arranged in vertical columns and horizontal rows, each of said finger-pieces being adapted to open communication with one of the mains corresponding to the column and one of the 40 mains corresponding to the row in which said finger-piece is located, whereby upon the operation of any finger-piece, pressure will be admitted for the operation of punches in each of the sets corresponding to the column and 45 row in which the finger-piece is located; substantially as described.
